CLAIM

The ornamental design for an advertising disc, as shown and described.

DESCRIPTION

FIG. 1 is a top, back, and left side perspective of an embodiment of an advertising disc embodying my new design.

FIG. 2 is a back elevation view thereof.

FIG. 3 is a right side elevation view thereof; and,

FIG. 4 is a reduced scale top, front, and right side perspective thereof on a toy robot.

Portions shown in broken lines are for illustrative purposes only and form no part of the claimed design.
